BED BATH

Charles Arthur Hoffman, Oakland, Calif.

Application November 9, 1948, Serial No. 59,178

3 Claims. (Cl. 4—177)

1

The invention, in general, relates to equipment especially useful in and around hospitals and more particularly relates to an improved bath equipment highly efficacious in physiotherapy and hydrotherapy in cases of invalidism or semi-invalidism.

The bathing as well as hydrotherapeutic treatment of patients unable to make use of their limbs or to move about because of back or other ailment rendering them paralyzed or partially paralyzed is an arduous task often detrimental to the convalescence and recovery of patients. Hydrotherapeutic treatment of bed-ridden patients has, heretofore, been almost an impossibility due to lack of desirable equipment and, when accomplished under present methods the patient is usually left in an extremely exhausted state. Even the bathing of paralytics under present methods and using equipment now available is highly undesirable since it is usually accomplished more or less piece-meal in that various portions of the patient's body are washed in step by step stages to the discomfort of the patient because being constantly moved about for appreciable periods of time until bathing is completed. The present invention is directed to the provision of equipment which not only obviates inherent disadvantages heretofore encountered in the bathing of paraplegics but also which affords efficacious means for hydrotherapeutic as well as physiotherapeutic treatment of invalids and semi-invalids.

A primary object of the invention is to provide an improved bed bath, especially suitable for the bathing as well as hydrotherapeutic treatment of paralytics, which can readily be set up and employed upon the patient's bed without undue discomfort to the patient and which greatly facilitates the bathing and treatment on the part of the hospital staff.

Another important object of my invention is to provide an improved bed bath of the indicated nature which is additionally characterized by its collapsible and simple construction enabling the bath to be readily set up for use on a bed and as readily dismantled for storing or transporting.

A still further object of the present invention is to provide a collapsible bed bath of the aforementioned character which is leak-proof, durable and yet of light-weight construction for facilitating the handling and use thereof as well as enabling it to be mounted upon a conventional hospital or other type bed without likelihood of damaging the bed.

Another object of the invention is to provide a bed bath of the indicated nature which is especially suitable and adaptable to hospital use for physiotherapy and hydrotherapy in cases of invalidism or semi-invalidism, and which greatly relieves the heavy burden upon nurses and others in the handling of the patient during such treatments with a minimum of discomfort to and minimum movement of the patient.

2

Other objects of the invention, together with some of the advantageous features thereof, will appear from the following description of a preferred embodiment which is illustrated in the accompanying drawings. It is to be understood, however, that I am not to be limited to the precise embodiments shown, nor to the precise arrangement of the various parts thereof, as my invention, as defined in the appended claims, can be embodied in a plurality and variety of forms.

Referring to the drawings:

Fig. 1 is a perspective view of a preferred embodiment of the invention, exclusive of the water-retaining walls of the equipment.

Fig. 2 is a sectional, side elevational view of a preferred embodiment of the invention with drain attachment.

Fig. 3 is an enlarged, fragmentary detail, of a corner of the equipment illustrating the manner of reinforcement thereof.

Fig. 4 is an end elevational view of the preferred embodiment of the invention.

Fig. 5 is a perspective view of the preferred embodiment of the invention fully set up for use and illustrating the filling and draining attachments.

Fig. 6 is a view of a portion of the frame of the preferred embodiment of the invention, in dismantled state for packing and transportation.

Fig. 7 is a development of the preferred embodiment of the invention illustrating the method of stacking and arranging the various elements for storing or transporting the same in an enclosing case.

Fig. 8 is a perspective view of the dismantled and packed preferred embodiment of the invention, not visible, enclosed within a transporting case.

In its preferred form, the improved bed bath of the present invention preferably comprises a collapsible frame, a water-retaining receptacle of flexible material removably suspended on said frame; said receptacle having a drain outlet therein, together with means on said frame for maintaining the walls of said receptacle in a tautened condition in operative position whereby deformation thereof under water pressure is effectively resisted, and means for rapidly filling and draining the said receptacle.

As particularly illustrated in Figs. 1 to 3 inclusive of the annexed drawings, the improved equipment of my invention for use in the handling, bathing and treatment of paraplegic patients comprises two main elements; namely, a collapsible frame, designated generally by the reference numeral 11, and a collapsible, flexible container or receptacle, designated generally by the reference numeral 12. The frame 11 preferably is fabricated from metal tubular bars and consists of two complementary half-sections 13 and 14 which are adapted to be detachably secured together at the approximate longitudinal center of the complete frame by means of tele-

scopic fitting of the sections together as well as by means of latching elements hereinafter described.

The half-sections 13 and 14 of frame 11 are of generally similar construction in that half-section 13 consists of an end portion comprising a pair of spaced, parallel arranged bars 16 and 17, together with a transversely disposed brace rod 18 spanning bars 16 and 17 approximately at the longitudinal centers thereof and preferably welded thereto. The half-section 13 of the frame 11 also includes two half-side portions, designated generally by the reference numerals 19 and 20, each consisting of a pair of spaced bars 21, 22, 23 and 24 with the corresponding bars 21 and 22 of half-side 19 as well as the corresponding bars 23 and 24 of half-side 20 arranged in parallel relationship as well as spaced apart, as shown. In addition, each half-side portion of the frame half-section 13 is provided with spaced transverse brace rods 25 spanning the spaced parallel bars of such sections and preferably welded thereto. As illustrated, the bar 16 of the end portion of frame half-section 13 spans the bars 21 and 23 of the side portions and is pivotally connected to each of said bars by means of suitable pivot or hinge pins 26 and 27, respectively. Similarly, the bar 17 of the end portion of frame half-sections 13 spans the bars 22 and 24 of the half-side portions and is pivotally connected to such bars by means of suitable pivot or hinge pins 28 and 29, respectively. Suitable lock-nuts 30 are provided for securing the pivot pins 26 to 29 inclusive in position.

Frame half-section 14 has a generally similar construction as half-section 13 of frame 11, and includes an end portion comprising a pair of spaced, parallel arranged bars 36 and 37, together with a transversely disposed brace rod 38 spanning bars 36 and 37 at their approximate longitudinal centers and preferably welded thereto. The half-section 14 of frame 11 also includes two half-side portions, designated generally by the reference numerals 39 and 40, each consisting of a pair of spaced bars 41, 42, 43 and 44 with the corresponding bars 41 and 42 of half-side portion 39 as well as the corresponding bars 43 and 44 of half-side portion 40 arranged in spaced, parallel relationship, as shown. In addition, each half-side portion of the frame half-section 14 is provided with spaced, transverse brace rods 45 spanning the spaced parallel bars of such sections and preferably welded thereto. As illustrated, the bar 36 of the end portion of frame half-section 14 spans the bars 41 and 43 of the half-side portions, and is pivotally connected to each of said bars by means of suitable pivot or hinge pins 46 and 47, respectively. Similarly, the bar 37 of the end portion of frame half-section 14 spans the bars 42 and 44 of the half-side portions and is pivotally connected to such bars by means of suitable pivot or hinge pins 48 and 49, respectively. Suitable lock-nuts 50 are provided for securing the pivot pins 46 to 49 inclusive in position.

In accordance with the present invention, latching means are provided for removably securing together the complementary frame half-sections 13 and 14 of the frame 11 in upright and operative positions. To this end, the side portions of one frame half-section, say the bars 21 to 24 inclusive of frame half-section 13, are formed with reduced free, inner ends, as indicated at 51 in Fig. 6 of the drawings, in order that such reduced ends 51 may be telescopically

fitted into the complementary tubular bars 41 to 44 inclusive of the frame half-section 14 which are of uniform cross-section throughout. Moreover, lips 52 are provided on the inner ends of at least two of the bars, say the bars 41 and 43, of the side portions of frame half-section 14, for releasably receiving links 53 pivotally carried on latching elements 54 which are, in turn, pivotally mounted on the inner ends of the bars 21 and 23 of frame half-sections 13 adjacent to their inner, reduced ends 51. In setting up the frame 11 for use, the frame half-sections 13 and 14 are first placed in an upright position and the half-side portions of each frame half-section are swung relative to their corresponding end portions on pivot or hinge pins 26 to 29 inclusive as well as pins 46 to 49 inclusive to bring the half-side portions of the two half-sections 13 and 14 into alignment with one another and substantially normal to their end portions. Then, the two half-sections are moved together with the reduced ends 51 of bars 21 to 24 inclusive telescopically fitted into the tubular bars 41 to 44 inclusive of the frame half-section 14. The links 53 of the latching means are then swung over and under the lips 52 on bars 41 and 43 and the tongues 55 of the latching elements 54 depressed to urge the links 53 tightly under the lips 52 and to lock them in such position where they will remain until the tongues 55 of latching elements 54 are raised to release the links from the lips, whereupon the frame 11 can as readily be dismantled as set up. To lend rigidity to the frame 11 in its set-up, operative position, I have provided a series of conventional hooks 56 and eyes 57 at the four corners of the frame which can be fastened together and unfastened at will.

As particularly illustrated in Fig. 1 of the annexed drawings, I preferably form the extremities of the side bars of each of the frame half-sections 13 and 14 so as to afford substantially flat stacking of these half-sections when the frame 11 has been dismantled and each of the half-sections folded upon itself. To this end, the side bars 21 and 22 of frame half-section 13 and the side bars 41 and 42 of frame half-section 14 are preferably off-set inwardly, as indicated at 58 and 59, at their extremities adjacent to their connections with their corresponding end portions, while the bars 23 and 24 of half-section 13 and the bars 43 and 44 of half-section 14 are off-set outwardly, as indicated at 61 and 62, at their extremities adjacent to their connections with their corresponding end portions of the frame. In Fig. 6 of the drawings, I have shown frame half-section 13 in dismantled and folded condition for storing or transporting, which view illustrates the advantageous frame construction just alluded to for effecting substantially flat stacking and packing. Frame half-section 14 is similarly foldable in dismantled form; the two folded half-sections being illustrated at the left and right of Fig. 7 wherein I have depicted a flexible case 63 of canvas or similar water-proof material in which the various members and elements of my improved bed bath can be encased for storing and transporting. As shown in Fig. 8, suitable fastening straps 64 as well as a carrying handle 65 are provided with the flexible case 63 for convenience of carrying as well as for tightly holding the elements of the bed bath therein.

The flexible container or tank 12 which I preferably employ in the preferred embodiment of the present improved bed bath comprises a rectangular sheet of water-proof material, prefer-

ably commercially available rubber sheeting, which is provided with a series of spaced grommets 71 along all edges thereof for receiving conventional shower curtain rings or hooks 72, or the like, whereby the receptacle or tank 12 may be removably suspended from the frame bars 21, 41, 36, 43, 23 and 16, as clearly illustrated in Figs. 2 and 5 of the annexed drawings. The pressure of what filling or partially filling the container or tank 12 will hold the sheet in a tautened condition, and this tautening of the sheeting is augmented by the transverse bars 25 and 45 along the sides as well as by transverse bars 18 and 38 at the ends thereof; the sheeting being sufficiently strong to resist deformation and leakage. The sheet is of sufficient width and length to permit over-lapping at the four corners of the tank, as clearly shown in Figs. 3 and 5, thereby affording reinforcement means, and suitable male and female snap fasteners 73 are provided at such corners for securing the sheeting in over-lapped condition at such points. Moreover, the sheeting 12 is provided with a drain outlet 74 therein at such location as to be disposed in the defined bottom thereof and adjacent one corner thereof, as shown in Fig. 5, and with which a suitable drainage hose 76 may be placed in communication by suitable coupling element, not shown, for carrying the drainage away from the tank. Preferably, I provide with the preferred embodiment of the present invention a commercially available automatic pump for filling as well as draining the tank 12 rapidly and effectively; such automatic pump means being marketed under the trade-mark "Siph-O" and comprising the hose 76 together with a detachable adapter 77, see Fig. 7, having a rotatable valve therein, not shown, for controlling water flow therethrough. The automatic pump element is readily fitted either to a screw-bib threaded faucet or to a smooth type faucet as the end 78 thereof is suitably threaded and shaped to effect such connections. The cone-shaped outlet end 79 of the adapter 77 is rotatable for operating the valve of such unit and in one position of the valve, with the adapter attached to a source of water, such as to a faucet outlet, water can be drained from the tank 12 by force of vacuum or suction through water pressure in the line to which the adapter is connected. In the opposite position of the valve of the adapter 77, water flow is directed through the adapter and hose 76 directly into the tank 12 to fill the same; it being understood, of course, that hose 76 is first detached or unfastened from the drainage outlet 74 and the latter closed with a plug, not shown. To drain the tank 12 rapidly after use, the outlet plug is removed and hose 76 placed in communication with drain outlet 74, and the valve of the adapter 77 adjusted. Thereafter, the faucet to which the adapter 77 is connected is turned on and by force of vacuum created by water pressure, the tank 12 is automatically and rapidly emptied. To complete the tank 12 unit of the bed bath, I have provided a flexible pillow 81, which preferably comprises a standard water bag that can readily be filled and emptied through its capped outlet and inlet 82, see Figs. 2 and 7 of the drawings.

The improved bed bath of my present invention, because of its relatively light-weight construction as well as because of the collapsible nature thereof, can readily and easily be set up as well as taken down, and can effectively be set up on a patient's bed without discomfort or in-

convenience to the patient and without damaging the patient's bed even when filled with water as the total filled weight thereof is easily supported by a conventional hospital bed. My improved bed bath has been successfully employed in a military hospital at the Presidio at San Francisco in connection with the treatment of paraplegic cases, and has been approved by nurses and doctors alike. The bed bath is highly efficacious for under water hydrotherapy for exercising paralyzed persons, and also for immersing a patient having heart trouble or affected with nervous disorders in relaxing warm water. Because of its construction and its collapsible features, the entire bed bath can be set up as well as dismantled, assembled and packed in a space in from three to five minutes. Because of its light weight, the bed bath can be carried about with ease.

20 It is to be understood that the appended claims are to be accorded a range of equivalents commensurate in scope with the advance made over the prior art.

I claim:

- 25 1. A bed bath comprising a collapsible frame consisting of a pair of complementary frame half-sections removably fastened together; each of said frame half-sections consisting of an end portion and a pair of half-side portions, a water-
30 retaining flexible container removably suspended on said frame; said container having a drain outlet therein, and means for enhancing the rigidity of said frame when said container is filled with water.
- 35 2. A bed bath comprising a collapsible frame, and a water-retaining container removably suspended on said frame; said collapsible frame comprising a pair of complementary frame half-
40 sections each consisting of an end portion of spaced parallel tubular bars pivotally connected to a pair of half-side portions consisting of spaced, tubular bars; one of said frame half-
45 sections being formed with half-side portions having reduced extremities for telescopically fitting the tubular bars of the other pair of half-side portions of the other frame half-section, and releasable latching means on said frame for fastening said sections together in upright, usable positions.
- 50 3. A bed bath as defined in claim 2, the tubular bars of one of said frame half-sections being offset inwardly adjacent to their connections with said end portion, and the tubular bars of the other of said frame half-sections being offset
55 outwardly adjacent to their connections with their corresponding end portion whereby the frame may be stacked upon its collapse.

CHARLES ARTHUR HOFFMAN.
